ELECTRIC CRAYON HOLDER

Harry Disko, Park Ridge, Ill., assignor to Marvin Glass
& Associates, Chicago, Ill., a partnership

Filed Aug. 17, 1967, Ser. No. 8,301

Term of patent 14 years

(Cl. D25—1)

The broken line showings of a crayon are for illustrative purposes only.

I claim:

The ornamental design for an electric crayon holder, substantially as shown and described.
